UNITED STATES PATENT OFFICE

SAMUEL B. ROBINETTE, OF PRINCETON, WEST VIRGINIA, ASSIGNOR OF ONE-HALF TO
CLIO TALIAFERRO PORTER, OF PRINCETON, WEST VIRGINIA

STRIPING BRUSH AND HOLDER

Application filed February 2, 1929. Serial No. 337,100.

The general object of this invention is to provide means whereby a perfect stripe of any desired size, either double, single, narrow or broad may be laid either as means for filling in space between previously laid stripes or around the edges of ventilators, cut moulds or bands or in any position required, the striper eliminating the expense of employing high priced painters to do the work by hand and permitting an inexperienced person to do the work faster and more accurately than is possible by a free hand drag brush.

A further object is to provide a device of this character having a brush support provided with a balancing portion or extension which, in actual practice, has been found to so balance the device that a remarkably straight line can be pulled or drawn without the use of any guiding device.

20 A further object is to provide in connection with the brush support a guide plate carried upon the brush support and adjustable toward or from the same which may be engaged as for instance against the edge of a moulding 25 to run a stripe parallel to this moulding.

Other objects will appear in the course of the following description.

My invention is illustrated in the accompanying drawing, wherein:

30 Figure 1 is a side elevation of a striping brush and holder constructed in accordance with my invention;

Figure 2 is a similar view to Figure 1, but taken on the opposite side of the device;

35 Figure 3 is a plan view of the device.

Referring to the drawing, 10 designates what I would call the brush holder which is formed of a thin plate of metal nearly rectangular in contour and having a straight lower edge 11. This plate at its rear upper corner has an extension 12 which is curved upward and rearward and then slightly downward, this extension being the same thickness as the plate 10. The forward edge 40 of the plate 10 is cut so as to extend downward and forward as at 13. The brush to be used with this holder comprises a ferrule 14 and the brush hairs 15, this brush portion proper being preferably of camels' hair with the brush cut more or less on a diagonal line

upward toward the rear edge of the brush ferrule.

The plate 10 may be provided with outwardly extending stud bolts but, as illustrated, screw bolts 16 pass through apertures in the plate 10 and through a guide plate 17 which has approximately the same form as the plate 10 but does not have any extension 12. This guide plate is spaced from the plate 10 by means of inner nuts 18.

Exteriorly of the plate 17, the screw bolts 16 are provided with nuts 19 so as to hold the plate 17 firmly in place. The plate 17 is preferably vertically slotted as at 20 for the passage of the screw bolts 16 and so as to permit the plate to be adjusted up or down.

In the use of this device, the brush consisting of the ferrule 14 and the brush hairs 15 should be worked out in paint to the right consistency. The brush is then laid on the outer face of the plate 10 so that the hairs will project slightly beyond the lower edge of the plate. The paint will cause the brush to adhere to the plate. The device is then taken in the right hand with the thumb of the right hand bearing against the brush ferrule 14 and the implement is drawn toward the operator in order to form the stripe.

The size of the stripe is easily regulated by raising or lowering the thumb. Where the guide plate is used, it is adjusted to any desired width from the plate 10 either so that the guide plate will engage against the outer edge of a moulding or so that the moulding will be embraced between the guide plate 80 and the plate 10. The guide plate as before remarked can be lowered so as to catch the edge of mouldings or hoods of ventilators.

A large variety of stripes and lines can be produced with this device by increasing 90 or decreasing the pressure upon the brush. When the plate 10 is separated from the guide plate 17 sufficiently so as to catch the edges of the moulding of an automobile body and by using a wide and soft brush between the 95 two plates, the striper may be used to paint the entire moulding, the edges of the plates 10 and 17 preventing the paint from spreading to the body in which the moulding is formed and assuring a clean smooth edge.

A further important feature of this device is the extension 12. Inasmuch as the device is so balanced by the long curved extension, a remarkably straight line can be pulled without the guide plate.

5 5 This device has been used particularly for striping automobiles and is found to be particularly effective in use.

10 While I have illustrated certain specific form for the device and certain details of construction, I do not wish to be limited to these as it is obvious that many minor changes might be made without departing from the spirit of the invention as defined in the appended claims.

15 I claim:—

20 1. A striping device comprising a pressure supporting plate having a rearward extension acting as a balance, the plate having a flat brush supporting face, and a flat thin striping brush adapted to be disposed against said plate and having a thin flat, ferrule adapted to be held in place against the plate by the thumb of the operator.

25 2. A striping device comprising a pressure supporting plate having a rearward extension acting as a balance, the plate having a flat brush supporting face, a brush adapted to be disposed against said plate and held in place thereon by the thumb of the operator, and a guide plate disposed parallel to the first named plate and in spaced relation thereto, on the opposite side from the brush supporting face of the plate.

30 3. A striping device comprising a pressure supporting plate having a rearward extension acting as a balance, the plate having a flat brush supporting face, a brush adapted to be disposed against said plate and held in place thereon by the thumb of the operator, and a guide plate disposed parallel to the first named plate and in spaced relation thereto on the opposite side of the plate from the brush supporting face, said guide plate being adjustable toward or from the first named plate.

35 4. A striping device comprising a pressure supporting plate having a rearward extension acting as a balance, the plate having a flat brush supporting face, a brush adapted to be disposed against said plate and held in place thereon by the thumb of the operator, and a guide plate disposed parallel to the first named plate and in spaced relation thereto and on the opposite side of the first-named plate from the brush supporting face, said guide plate being adjustable toward or from the first named plate and adjustable in a plane parallel to the plane of the first named plate.

40 5. A striping device of the character described, comprising a flat plate adapted to support a brush upon one face with the edge of the brush projecting below the edge of the plate, the plate having bolts projecting outwardly from the face of the plate opposite

to the brush supporting face thereof, nuts disposed upon the bolts, a vertically slotted guide plate mounted upon the bolts and engaged by the nuts to hold the guide plate in place.

6. A striping device of the character described, comprising a flat plate adapted to support a brush with the edge of the brush projecting below the edge of the plate, the plate having bolts projecting outward from the face of the plate opposite the brush supporting face thereof, nuts disposed upon the bolts, a vertically slotted guide plate mounted upon the bolts and engaged by the nuts to hold the guide plate in place, the first named plate having an upwardly and rearwardly curved extension having a thickness the same as that of the plate.

70 75 In testimony whereof I hereunto affix my signature.

80 SAMUEL B. ROINETTE.
